United States Patent

Des. 236,569
Patented Sept. 2, 1975

236,569

PLANT TROUGH

Friso Kramer, Amsterdam, Netherlands, assignor to Wilk-hahn-Wilkening & Hahne, Einbeckhausen, Germany

Filed May 8, 1973, Ser. No. 358,376

Claims priority, application Denmark Nov. 9, 1972

Term of patent 14 years

Int. Cl. D6—99

U.S. Cl. D6—182

FIG. 1.

FIG. 2.

FIG. 3.

FIG. 4.

FIG. 1 is a perspective view from above and one end of a plant trough showing my new design;

FIG. 2 is an elevational view showing one of the two identical ends of FIG. 1;

FIG. 3 is a rear elevational view of the plant trough of FIG. 1; and

FIG. 4 is an under plan view of the plant trough of FIG. 1.

I claim:

The ornamental design for a plant trough, as shown and described.
